JOHANNES JACQUES NUMANS, OF EINDHOVEN, NETHERLANDS, ASSIGNOR TO RADIO CORPORATION OF AMERICA, A CORPORATION OF DELAWARE

MODULATING SYSTEM

Application filed May 21, 1927, Serial No. 193,201, and in the Netherlands May 22, 1926.

The invention relates to a circuit arrangement for modulating the oscillations generated or amplified by a thermionic device, for example, for periodically interrupting or 5 altering these oscillations by means of a signal-key or for acoustically modulating these oscillations with the aid of a microphone or similar device.

The invention has for its object a circuit 10 arrangement which permits low tensions to be applied continuously to the modulating member so that under all circumstances there is no danger in touching it even with transmitters of large outputs which are operated 15 with high tensions and comparatively heavy currents because of their large outputs. The invention has also for its object to prevent the production of strong sparks so that signals can be transmitted with great rapidity.

According to the invention, this purpose 20 is attained by so arranging the circuit that the modulating member acts upon the internal resistance of a first auxiliary triode connected in series with an ohmic resistance 25 which forms part of the grid circuit of a second auxiliary triode which in its turn forms part of the grid leak of the first-mentioned thermionic device.

Further features of the invention will appear from what follows and the invention 30 will be explained in detail with reference to the accompanying drawings in which;

Figs. 1 and 2 show embodiments of the modulating system. In the figures which 35 only represent two embodiments of the principle of the invention, O is a triode which serves to generate the desired oscillations or to amplify the oscillations generated by a preceding triode, and which is connected in 40 the manner known for that purpose. Of this known circuit-arrangement only a grid condenser C is shown.

The grid leak consists of a self induction coil L connected in series with an ohmic resistance W the whole of it being connected 45 in series with a triode T H. Moreover, an ammeter A is joined to the arrangement in order to be able at any instant to verify the value of the grid currents of the oscillator O. The grid circuit of the auxiliary triode T

H comprises a grid biasing battery V B and an adjustable ohmic resistance R, the dimensions being so chosen that under the influence of the negative potential of the grid of the triode T H owing to the tension of the 55 battery V B the internal resistance of the said triode is just sufficient to cause grid currents of the desired value to flow in the oscillator O. When the negative potential of the grid of the triode T H increases with 60 respect to the filament, the internal resistance of this triode increases and the grid currents in O decreases. This increase of the negative potential of the grid of the triode T H is effected with the aid of a first auxiliary 65 triode E H, which is connected in series with a source of potential S, with a resistance R and with the discharge path cathode-anode of the secondary auxiliary triode T H. In the example illustrated in Fig. 1 the source 70 of potential S is a source of direct current keeping in mind the rectifying properties of the triodes E H and T H, this source S may be replaced by an alternating current source, for example, by a transformer as illustrated 75 in Fig. 2. In that case, the frequency of this alternating current source should preferably be chosen so as to lie in the ultra-audible region. In the grid circuit of the triode E H is included a battery B which has its negative 80 pole connected to the grid and its positive pole to a modulator M which, in the example illustrated, is a signal key but it may be any form of modulator.

Furthermore the grid and the cathode of 85 the first auxiliary triode E H are mutually connected by a leakage resistance L W.

The operation of the invention is as follows:

When the key is pressed down, the grid of 90 the triode E H has a negative potential equal to the potential of the battery B. This potential is chosen so that the internal resistance of the triode E H practically becomes infinitely great, and therefore the source of 95 current S cannot supply current.

When the key is released, the charge on the grid of the triode E H leaks away along the leakage resistance L W and the current of the battery S is allowed to pass. This cur- 100

rent takes then the following path: from S thru E H, A, T H and R back to S. This current flow causes a voltage drop to occur in R which results in the potential of the grid of the triode T H becoming more negative with respect to the filament which has the abovementioned influence on the grid currents in O. When the key M is pressed down again, the grid of the triode E H becomes negative again and the current from the source of current S stops flowing so that the potential of the grid of the triode T H is also restored again to its normal value.

It will be evident that the circuit-arrangement can also be used for telephony purposes, in which case the key M need only be replaced by a microphone of suitable size.

The circuit-arrangement affords the advantage that at the modulator M only very slight potentials and break-induced currents are concerned. The working contact of the key can even be earthed without any disadvantage. The closing and the interruption of the current are effected without any appreciable inertia so that even in that respect the arrangement has advantages over the known interruption relays which, because of their high tensions, have their contacts so widely spaced apart that the transmission of signals can only take place slowly.

The E. M. F. of the source of potential S should be rather high (for example, of the order of magnitude of some thousands of volts) as during the time intervals between the signalling periods, the average grid potential of the triode O is determined thereby and it is desirable to keep this potential strongly negative.

What I claim is:

1. A circuit arrangement for modulating oscillations, comprising an oscillating tube, a grid leak for said tube, a modulating member, an auxiliary triode, a second auxiliary triode having its filament conductively connected to the grid of said oscillating tube, and an ohmic resistance which forms part of the grid circuit of the second auxiliary triode, the modulating member acting upon the internal resistance of the first auxiliary triode, the first auxiliary triode, the ohmic resistance which forms part of the grid circuit of the second auxiliary triode, and the second auxiliary tube being connected in series, the second auxiliary triode forming part of the grid leak of the oscillating member.

2. A circuit arrangement for modulating oscillations, comprising an oscillating tube, a grid leak for said tube, a modulating member, an auxiliary triode, a second auxiliary triode, an ohmic resistance which forms part of the grid circuit of the second auxiliary triode, the modulating member acting upon the internal resistance of the first auxiliary triode, the first auxiliary triode being connected in series with the ohmic resistance

which forms part of the grid circuit of the second auxiliary triode, the second auxiliary triode forming part of the grid leak of the oscillating member, and a source of potential conductively connected between the grid and the cathode of the first auxiliary triode so as to be in series with the modulating member. 70

3. A circuit arrangement for modulating oscillations, comprising an oscillating tube, a grid leak for said tube, a modulating member, an auxiliary triode, a second auxiliary triode, an ohmic resistance which forms part of the grid circuit of the second auxiliary triode, the modulating member acting upon the internal resistance of the first auxiliary triode, the first auxiliary triode being connected in series with the ohmic resistance which forms part of the grid circuit of the second auxiliary triode, the second auxiliary triode forming part of the grid leak of the oscillating member, a source of potential connected between the grid and the cathode of the first auxiliary triode so as to be in series with the modulating member, and a leakage resistance arranged between the grid and 90 the cathode of the first auxiliary triode. 95

4. A circuit arrangement for modulating oscillations, comprising an oscillating tube, a grid leak for said tube, a modulating member, an auxiliary triode, a second auxiliary triode, an ohmic resistance which forms part of the grid circuit of the second auxiliary triode, the modulating member acting upon the internal resistance of the first auxiliary triode, the first auxiliary triode being connected in series with the ohmic resistance which forms part of the grid circuit of the second auxiliary triode, the second auxiliary triode forming part of the grid leak of the oscillating member, the ohmic resistance which forms part of the grid circuit of the second auxiliary triode also forming part of the discharge cathode anode path of the first auxiliary triode, and a source of direct current potential, the plate circuit of the first 100 auxiliary triode being connected in series with the source of direct current potential. 105

5. A circuit arrangement for modulating oscillations, comprising an oscillating tube, a grid leak for said tube, a modulating member, an auxiliary triode, a second auxiliary triode, an ohmic resistance which forms part of the grid circuit of the second auxiliary triode, the modulating member acting upon the internal resistance of the first auxiliary triode, the first auxiliary triode being connected in series with the ohmic resistance which forms part of the grid circuit of the second auxiliary triode, the second auxiliary triode forming part of the grid leak of the oscillating member, the ohmic resistance which forms part of the grid circuit of the second auxiliary triode also forming part of the discharge cathode anode path of the first auxiliary triode, and a source of direct cur- 115 120 125 130

rent potential, the plate circuit of the first auxiliary triode being connected in series with the source of direct current potential, the grid of the second auxiliary triode being biased.

- 5 6. In a circuit arrangement for modulating oscillations an oscillation tube, a grid leak for said tube comprising an inductance a fixed resistance and a variable resistance all
10 connected electrically in series, an auxiliary triode, a source of potential connected between the grid and the cathode of said auxiliary triode, a modulating means adapted to vary the internal resistance of said auxiliary triode and means controlled thereby for varying the value of said variable resistance in accordance therewith.
